Esq.

(57) **CLAIM**

The ornamental design for an electronic storage case for mobile communications device, as shown and described.

DESCRIPTION

FIG. 1 is a front perspective view of an electronic storage case for mobile communications device showing our new design with the slideable cover in the closed position. FIG. 2 is a rear perspective view thereof with the slideable cover in the closed position. FIG. 3 is a top view thereof with the slideable cover in the closed position. FIG. 4 is a bottom view thereof with the slideable cover in the closed position. FIG. 5 is a right-side view thereof with the slideable cover in the closed position. FIG. 6 is a left-side view thereof with the slideable cover in the closed position. FIG. 7 is a front elevation view thereof with the slideable cover in the closed position. FIG. 8 is a rear elevation view thereof with the slideable cover in the closed position. FIG. 9 is a front perspective view thereof with the slideable cover in an open position. FIG. 10 is a rear perspective view thereof with the slideable cover in an open position. FIG. 11 is a top view thereof with the slideable cover in an open position. FIG. 12 is a bottom view thereof with the slideable cover in an open position. FIG. 13 is a right-side view thereof with the slideable cover in an open position. FIG. 14 is a left-side view thereof with the slideable cover in an open position. FIG. 15 is a front view thereof with the slideable cover in an open position. FIG. 16 is a rear view thereof with the slideable cover in an open position. FIG. 17 is a front perspective view thereof in a state of use with an environmental mobile communications device and with the slideable cover in the closed position; and, FIG. 18 is a rear perspective view thereof in a state of use with an environmental mobile communications device and with the slideable cover in an open position. The obliquely-shaded rectangular rear surface shown in FIGS. 2, 8, 10, and 16 is a display screen. The broken lines in FIGS. 17–18 depict an environmental mobile communications device that forms no part of the claimed design.
